PLATEN MECHANISM FOR PRINTING MACHINES

Carl J. Hueber, Cleveland Heights, Ohio, assignor, by mesne assignments, to Addressograph-Multigraph Corporation, Cleveland, Ohio, a corporation of Delaware

Application February 12, 1936, Serial No. 63,575

22 Claims. (Cl. 101—274)

This invention pertains to a printing machine, and especially to an improved platen or impression mechanism therefor. More particularly, my invention is concerned with the provision of an improved roller-platen mechanism for use in printing machines, such as address printing machines. These, therefore, are the general objects of the present invention.

Generally in the past, series printing machines, such as address printing machines, have been provided with either one of two types of platens. One of these types is known as stamper or flat platen, and the other type is known as a roller platen. The stamper platens are mounted to be brought into contact with the entire area of the printing member, at one time, by a blow or stamping action.

A roller type of platen, printing by rolling action a line at a time, is capable of producing a clearer copy than the stamper platen, and has the further advantage that the impression more closely resembles a typewritten impression. The present invention is concerned with improvements in roller platens and the means for operating the same.

The usual roller type of platen comprises a roller having a rubber or similar impression making surface and is mounted at one end of an overhanging frame arm, the other end of such arm being pivoted to the main frame of the printing machine. Such a frame arm is swung about its pivot until the roller coacts with a work sheet superimposed above a suitable printing device, whereupon the roller is rolled across the work. An example of such a roller platen is shown in Patent #1,102,396, of Joseph S. Duncan, issued July 7, 1914, to my assignee, Addressograph Company. The present invention may be considered an improvement on the construction shown in that patent.

Roller platens have heretofore required more or less complicated operating mechanisms, as is evidenced by the patent above mentioned. Likewise, clarity and evenness of the impression have been impaired, both by the wear at the frame arm pivots, and by the warping of the arm. Cumbersome operating mechanisms have also been required to swing the frame arm, which itself has been made unwieldy, to minimize the flexing of the arm. Such operating mechanisms have also required comparatively large and expensive power units.

It is therefore an object of the present invention to provide a roller platen and a simple operating mechanism therefor, which may be sup-

ported on a stationary frame arm and which will make accurate impressions from various printing members, regardless of the arrangement or number of printing characters on such printing member.

Other objects of the invention will become more apparent from the following description, reference being had to the preferred embodiment of the invention, illustrated by the accompanying drawings. The essential and novel features of the invention will be summarized in the claims.

In the drawings, Fig. 1 is a side elevation of a comparatively small and compact printing machine, having a platen, a platen-supporting, and a platen-operating mechanism constructed in accordance with the present invention, certain parts of the machine being broken away to more clearly illustrate the internal construction thereof; Fig. 2 is a transverse, vertical section, on an enlarged scale, through the platen and its supporting mechanism, the plane of the section being indicated by the lines 2—2 on Fig. 1; Fig. 3 is a centrally located vertical section through the platen, as indicated by the line 3—3 on Fig. 2, the platen being in engagement with the work; Fig. 4 is a sectional view, taken in the plane indicated by the line 4—4 on Fig. 2, illustrating, however, the platen in a raised position, out of contact with the work sheet; Fig. 5 is a horizontal section, through the platen-supporting mechanism, illustrating the platen in plan view, certain parts being broken away to more clearly illustrate the internal construction thereof, the plane of the section being indicated by the lines 5—5 on Fig. 2; Fig. 6 is a substantially horizontal detail, being a section taken in the plane indicated by the line 6—6 on Fig. 4; Fig. 7 is a sectional detail, the plane of the section being indicated by the line 7—7 on Fig. 5; Fig. 8 is a detail, similar to Fig. 7, but illustrating the parts in the position they occupy when the platen is raised out of contact with the work sheet, namely, in its uppermost position.

I have chosen to illustrate my preferred platen, together with its supporting and operating mechanism in connection with a printing machine of the type shown and described in my prior application, Serial No. 62,416, filed February 5, 1936, and assigned to my assignee, Addressograph Company.

Referring now to Fig. 1, I indicate at 10, the main frame of an addressing machine, provided with a horizontal guideway 11, along which printing devices, such as address plates D, may be sup-

progressed one after the other from the bottom of a stack indicated at 12 to a supporting bed or stack indicated at 18. A suitable conveyor, such as a pair of reciprocating feed bars 14, is provided to progress the printing devices. Suitable mechanism, such as, for instance, an eccentric 15, driven by a motor M and connected by suitable links and levers 16, with the feed bars, may be used to periodically reciprocate such bars. 10 When the feed bars 14 move to the right (Fig. 1) suitable abutments 19 thereon engage the bottommost plate in the stack 12 and shove it along toward printing position, the same operation causing all plates in advance thereof to be moved, 15 one after another by a suitable spring-pressed pawl 17 carried by the feed bars 14, so that one after another of the printing devices come to rest on a support or anvil 13.

The platen-supporting mechanism comprises 20 a pair of spaced frame arms 20a and 20b, rigidly connected to the frame 10. Such arms may be an integral part of the frame, or may be secured thereto by suitable bolts, not shown. These arms extend from the magazine 12, at the rear 25 of the guideway 11, forwardly above and parallel with such guideway. Each platen arm is spaced apart from the other a distance slightly greater than the length of the printing devices, and is provided with an inwardly facing guide 30 rail 30.

The platen is of the roller type, as will hereinafter be more fully understood, and is carried by a platen carriage C, which is reciprocated along the guide rails 30 by a suitable mechanism, such as, for instance, an eccentric 31, which is driven by the motor M in timed relation with the eccentric 15, heretofore described. The eccentric 31 is drivingly connected by a crank 32 with a pair of levers, one of which is shown at 40 33 in Fig. 1, and both of which are pivotally mounted on a rod 34, supported by the frame 10. Each lever 33 carries, on its upper end, a pin 35. These pins are arranged to be engaged by notches 36, formed at one end of respective 45 links 37, the other end of which is pivotally connected as at 38 with a platen carriage C. Suitable springs 39 are interconnected between each link 37 and its respective lever 33, and serve to normally maintain the links connected with their 50 levers, providing a safety feature hereinafter to be more fully described.

The platen comprises a roller 40, journaled by suitable anti-friction bearings 41, on a shaft 42, which is supported at either end of the roller, 55 by bushings 43, carried by respective links 44. The platen is provided with a segmental printing member or surface composed of rubber or other suitable material 45.

The platen links 44 are pivotally connected 60 to another pair of links 47 by a suitable rod 48. The links 47, in turn, are secured to a rock shaft 49, journaled in suitable bearings which have a universal connection with the platen carriage, hereinafter more fully described, but which permit adjustment of the printing pressure, as well 65 as adjustment of the transverse alignment between the platen-contact surface 45 with the work or printing device D.

The platen shaft 42 is also linked to a shaft 50, which is supported in suitable bearings formed in the platen carriage C. As shown, this connection comprises a pair of links 51, one end of each of which is fixed to the shaft 50, and the 70 other ends of which are pivotally connected to

the platen-supporting bushings 43, as indicated in Fig. 2.

The platen is normally maintained in the position shown in Fig. 4, where it will be noted that it is spaced some distance above the work-sheet W by a torsion spring 55 encircling the shaft 50 and having one end thereof, engaging the carriage C and the other end connected as at 56 (see Figs. 3 and 6) to a suitable nut which is locked to the shaft 50. 10

As heretofore mentioned, the platen rockshaft 49 is mounted in the carriage by universal bearing units which, as shown in Fig. 2, comprise a pair of spaced sleeves or bushings 59, in which the shaft is journaled. Each sleeve is provided 15 with a pin 60, arranged to occupy an axially extending arcuate recess 61, formed in the arms of respective yokes 62. Each yoke is provided with a stud 63, which threadingly engages a bushing 64, rotatably mounted in the carriage C, as illustrated in Fig. 2.

This arrangement is such that consequent upon the turning of both bushings 64, the platen will be raised and lowered as a unit, or consequent upon the turning of one bushing, one end of the 25 platen may be raised or lowered relative to the other end. Thus the platen is readily adjusted. Suitable locking nuts 65 threadingly coat with the respective bushings 64 and may be readily tightened to maintain the platen in its adjusted 30 position relative to the printing device supported on the anvil 13.

As heretofore mentioned, the carriage slides along rails 30, which are carried by respective frame arms 20a and 20b. As illustrated in Figs. 35 2 and 5, the carriage is provided at either side thereof with a pair of spaced rollers 66 arranged to engage the lower face of a guide-rail 30, and a roller 67 arranged to engage the upper face of 40 the frame arms, as indicated in Fig. 1, and are preferably pivotally connected therewith at their rearmost ends by suitable screws 68. The forward ends of these rails may be individually 45 raised or lowered by eccentric adjusting members 70, and clamped in an adjusted position by clamping screws 71. These adjusting members and clamping screws pass through suitable slots in their respective guide rails and engage 50 respective frame arms.

The platen, in its retracted position, is normally some distance above the work sheet. When, however, it moves toward the right, to the position indicated in Fig. 1, the foremost rollers 66 of the platen carriage engage, as shown in 55 Fig. 8, cam surfaces 72 of respective links 73 pivoted as at 74 to their respective guide-rails 30. This engagement rocks the links 73 in a counter-clockwise direction against the action of tension springs 75. Continued forward movement of the 60 platen carriage causes the ends 76 of the rod 48 to engage notches 77 formed at the ends of the respective links 73.

The contact between the walls of the notches 77 and the rod 48 causes the forward movement 65 of the rod to be retarded, whereupon the links 44, 47 and 51 are rocked about their respective pivots into the positions indicated in Figs. 7 and 3. This causes the platen to be lowered into contact with the work W, superimposed above an 70 inking ribbon R which overlies the printing device D supported by the anvil 13, thereby causing the platen to engage the work with printing pressure.

It will be noted that when the platen is in the 75

position shown in Fig. 3, the upper end of the links 44 abut shoulders 80, formed in their respective links 47, thereby causing the printing pressure to be applied independent of the pivotal connections between the links 44 and 47.

The platen assumes the position illustrated in Fig. 3, when it reaches the end of the right-hand stroke (Fig. 1) whereupon the platen carriage is drawn to the rear by the operating mechanism, heretofore described, to effect the printing. It will be noted that while the platen is being moved rearwardly, the spring 55 acts to maintain the links 44 and 47 in the position indicated in Fig. 3, thus making, in effect, a straightened 15 toggle.

As the platen carriage is drawn rearwardly by the links 37, the platen roller is positively rotated independent of the frictional contact between the platen and the work sheet to insure proper rolling action at all times, regardless of 20 variations in frictional contact between the work and platen, due to a varied number of printing characters. For this purpose, it will be noted, that the platen-supporting arm 20b is provided on its undersurface with a rack 89, 25 arranged to be constantly engaged by a gear 90, rotatably mounted on the shaft 59, which, as heretofore mentioned, is carried in a fixed axis relative to the platen carriage C.

As shown in Fig. 6, the gear 90 is drivingly secured to a bushing 91, rotatably mounted on the shaft 50. Likewise secured to the bushing 91 is a pinion 92, arranged to constantly engage a gear 93, rigidly fixed as shown in Fig. 2, to 30 the platen roller 40. The arrangement of this gearing is such as to cause the platen roller to engage the work sheet at all times with a perfect rolling action.

The roller 40, as heretofore mentioned, is provided with a segmental platen surface member 45, and is so arranged that the platen shaft 42 may be readily withdrawn, permitting this segmental surface to be adjusted angularly about the axis of the platen. This adjustment permits 45 the platen to be selectively arranged to print as many lines L of printing characters as may be desired, the arrangement being such that the foremost edge 85 of the platen member 45 will engage the first line of characters of the printing 50 device desired to be printed. For example, in Fig. 3 the platen has been set to first engage the second line of characters from the left, hence, as there shown, the last three lines will be printed and the first line omitted.

As illustrated in Figs. 2, 4 and 6, the left-hand end of the platen shaft 42 is provided with a knurled knob 86, which may be grasped to slide the platen shaft to the left (Fig. 2) freeing the platen from the carriage C, and permitting it to 55 be rotated relative to its driving gear 92, thereby determining which line of characters of the printing device will be first contacted by the platen.

The platen shaft is normally maintained in the position illustrated in Fig. 2, by a latch arm 97, which is pivotally mounted on the bushing 91, heretofore described, and is provided with a slotted opening, illustrated in Fig. 4, arranged 60 to engage a reduced portion 99 of the platen shaft 42, thereby normally preventing removal of the shaft. When it is desired to change the setting of the platen, the link 97 is swung in a clockwise direction (Fig. 4), out of engagement with 65 reduced portion 99 of the platen shaft, permit-

ting the shaft to be readily withdrawn by the operator.

When the platen has progressed far enough on its printing or left-hand stroke (Fig. 1) to have caused an impression to have been made 5 from the desired area of a printing plate D which rests on the anvil 13, the platen is automatically raised clear of the work. For this purpose I provide a pair of abutments 100 and 101, carried by the respective frame arms 20a and 20b, 10 and arranged to engage respective ends 76 of the rod 48, when the platen reaches the rearmost edge of the printing plate. Whereupon, continued rearward movement of the rod is momentarily stopped and the rearward movement of the 15 platen carriage C causes the linkage 43 and 47 and 51 to swing the platen from the position shown in Fig. 3 into the position shown in Fig. 4. When so raised, the shaft ends 76 are free to move to the left, as they are clear of the stops 20 100 and 101.

The upward movement of the platen is stopped by the engagement of a spacing sleeve 102, carried by the rod 48, with suitable abutments 103 formed in the front wall of the carriage C. 25

As heretofore mentioned, the platen may be moved so as to skip the first line, the first two lines, or the first three lines, etc. of characters on the printing device. The arrangement of the stops 100 and 101 is such that they may be adjusted so as to cause the platen to be raised from the printing plate at different points. Thus, they may be so fixed as to cause the platen to be raised from the printing plate after it has made an impression of any predetermined number of 30 adjacent lines, as, for instance, the middle two lines in Fig. 3. This is accomplished by securing the stops 100 and 101 on their respective platen-supporting arms 20a and 20b in such a manner that they may be readily adjustable, either toward the right or left, (Fig. 1) and secured in 35 adjusted positions by suitable set screws 104.

I have so arranged the platen mechanism that should the operator's fingers, or any unusually thick article lie beneath the roller platen, while 40 it is being urged downwardly to engage the work sheet with printing pressure, the platen will be disconnected from its driving mechanism, thereby preventing injury to the person of the operator or damage to the parts of the mechanism. 45 Such mechanism comprises the pin and slot connections 35, 36, between the platen-driving arms 33 and the links 37. It will be noted that the rearmost surfaces (Fig. 1) of the notches 36, are substantially normal or at right angles to the 50 direction of reciprocation of the links 37, whereas the foremost walls of the notches 36 are sloped, that is, set at an angle to the direction of reciprocation of the links.

I have found that a very small amount of power 55 is required to move the platen forwardly, that is, to the right in Fig. 1, and cause it to engage the work with printing pressure, whereas a greater amount of power is required to roll it across the work. Therefore the sloping walls of the notches 36 provide sufficient contact between the pins and links to enable the platen to be readily moved forwardly and downwardly to engage the work. However, if an obstruction is placed between the platen and the work sheet, the tension of the 60 springs 39 will be overcome and the sloping front walls will cam the links out of engagement with their respective pins 35, thereby breaking the power-driving connection to the platen. Thereafter, on the return stroke of the operating arms 75

33, these arms will automatically pass into the notches 36, and, by reason of the abrupt wall forming the rear of such notches, will become re-engaged to the links 37 and thus return the platen idly to its rear position, so that the machine is ready for normal operation on the succeeding stroke.

If desired, the platen shaft 42 may also carry a coaxial supplemental platen for printing dates, numbers, etc., from an impression member additional to the printing plates. Such supplemental platen is shown at 110 in Figs. 2 and 6, being equipped with roller bearings embracing the shaft 42. This supplemental platen is of slightly smaller radius than the segment 45 of the main platen, so that it may cooperate with a printing member 111 mounted on the bed of the machine at somewhat higher elevation than the printing plate.

20 It will be understood from the description given of this machine that the entire platen mechanism is carried by fixed rigid frame arms which may readily be made with sufficient stiffness to prevent any yielding action from the platen pressure; likewise these arms have sufficient area of contact with the main frame to prevent any yielding at their attachment to the main frame. By employing two spaced arms an open space is provided which may act as a magazine for the 25 stack of address plates or may receive a separate magazine, if desired.

It will also be observed that the platen is moved from its idle position down into active position so gradually that the force required is minimized. 35 When in active position, the platen is positively rotated on the printing stroke, avoiding possibility of slippage between it and the printing plate. The platen may be readily reset to start its printing at any line of the plate and when reset the 40 position is positively insured by the gearing described. Also the stoppage of the printing engagement of the platen at any desired point is readily and definitely effected. By reason of the mechanism which is utilized to adjust the beginning and ending of the printing stroke of the platen, it is immaterial if the actual travel 45 of the platen in either direction exceeds that required to make the impression. Finally, it may be noted that the adjustments provided enable the platen to be accurately positioned with reference to the plane of the printing member and 50 raised or lowered to effect the desired pressure, and enable the maintenance of this same pressure throughout the entire course of the rolling action.

55 I claim:

1. In a printing machine, means for supporting a form, a guideway extending above and parallel with said form, a carriage reciprocably mounted in said guideway for movement in a direction in a plane parallel with said form, a pair of links pivotally connected to the carriage, a second pair of links pivoted to the first-named links respectively and spaced apart from each other, a shaft journaled in the last-named pair of links, a roller platen rotatably supported on said shaft, resilient means normally acting to retain said links out of alignment with each other and thereby maintain the platen out of contact with the form; and periodically acting yielding means to act as a shock absorber and move the links of one pair into alignment with the links of the other pair to cause the platen to coat with said form.

75 2. In a printing machine, a frame having means

for supporting a form, a guideway rigidly secured to said frame and extending above and parallel with the form, a carriage mounted in said guideway for reciprocation in a plane parallel with said form, a shaft rotatably supported in said carriage, a pair of links secured to said shaft, a second pair of links pivoted to the first-named links respectively and spaced apart from each other, a second shaft removably journaled in the last-named pair of links, a segmental roller platen 5 coaxial with and rotatably supported on said last-named shaft, resilient means normally acting to retain said links out of alignment with each other and thereby maintain the platen out of contact with said form, a third pair of links pivotally connected to the platen shaft and to said carriage, to guide the movement of the platen, means to move the first-named pair of links into alignment with each other, thereby causing the platen to coat with said form. 20

3. In a printing machine, the combination with means to support a form, of a guideway extending in a plane substantially parallel with said form and thereabove, a carriage reciprocably mounted in said guideway, a roller platen, a pair of toggle links connected to said carriage and said platen respectively, means to reciprocate said carriage, a member pivoted to said guideway and acting consequent upon the approach of the limit of movement of the carriage in one direction to cause the platen to engage a work sheet, and means for yieldingly holding said member whereby it may act as a shock-absorber. 25

4. In a printing machine, the combination of 35 such frame, an arm fixedly secured to said frame, a platen carriage mounted on said arm for reciprocation in a plane substantially parallel with said form, a rotatable platen movably mounted in said carriage for movement to and from said form, means to reciprocate the carriage, means 40 acting consequent of reciprocation of the carriage to move the platen toward and away from the form, a rack carried by said guideway, gearing interconnecting said platen and rack to rotate said platen when in contact with the form. 45

5. In a printing machine, the combination of 50 means for supporting a form, a stationary guideway spaced above said form, a carriage mounted in said guideway, a roller platen, a pair of toggle links connected to said carriage and said platen, respectively, means to move said links to cause the platen to move into and out of contact with work superimposed on said form, a stationary 55 rack gearing connecting the rack and platen and operative irrespective of the position of the links and means to move the carriage in the guideway to cause the platen to roll across said form.

6. In a printing machine, the combination of 60 means for supporting a form, a stationary arm, a carriage reciprocable on the arm, a roller platen, a pair of toggle links connecting the platen with the carriage, a third pair of links each pivoted to the platen at the axis thereof and to the carriage, a stationary rack carried 65 by the arm, and a train of gearing connecting the rack and platen and including a gear coaxial with the pivot of the third link to the carriage.

7. In a printing machine, the combination with 70 means to support a form, a platen carriage, means for guiding it parallel with the form, a shaft, a roller platen carried thereby, two pairs of toggle links respectively connecting the platen shaft with the carriage, a second shaft on the 75

carriage, two links connecting said shaft with the platen shaft, a stationary rack and a gear train connecting it with the platen.

8. In a printing machine, the combination of means for supporting a printing form, a stationary arm, a reciprocable carriage mounted on the arm, a roller platen, toggles connecting the platen with the carriage means for straightening the toggles at the end of the stroke of the carriage to lower the platen to active position, means for reciprocating the carriage including a driving member and a driven member normally retained in engagement with each other by a spring adapted to yield and allow the operating member to clear the operated member in case of obstruction to the depression of the platen, said engagement of the driving member with the driven member being against an inclined surface in the direction to lower the platen and against an abrupt surface in the direction to raise the platen, whereby notwithstanding separation the parts will be automatically restored on the return stroke of the operating mechanism.

9. In a series printing machine, the combination of means for supporting printing devices one at a time in printing position, a stationary member, a roller platen carried by said stationary member for reciprocation in a plane parallel with the printing device in printing position and movable toward and away from the plane of said device, means acting consequent upon reciprocation of said platen to move the platen toward and away from work superimposed on said device, and control means for causing the same line of the platen to coact with the same line of the printing device on successive impressions.

10. In a printing machine, the combination of a frame having means for supporting a form, a rigid arm, rigidly secured to said frame at one end of the arm and having a projecting portion with a free end to provide a fixed guideway extending lengthwise of the projection spaced above the form, a platen carriage mounted on said guideway for reciprocation in a plane substantially parallel with the plane of said form, a platen mounted in said carriage for movement to and from said form, means to reciprocate the carriage, and means acting consequent on the reciprocation of said carriage to move the platen toward and from the form.

11. In a printing machine, the combination of means for supporting a form, a stationary guideway spaced above said form, a carriage mounted in said guideway, a roller platen, a pair of toggle links interconnected by a pivot pin and connected to said carriage and said platen respectively, and provided with abutting surfaces arranged to receive the thrust when the links are aligned, means adapted to engage the pivot pin of said links to move said links and thereby cause the platen to move into and out of contact with work superimposed on said form, and means to move the carriage along the guideway to cause the platen to roll across said form.

12. In a printing machine, the combination with means to support a form, of a guideway, a carriage mounted in said guideway for reciprocation in a plane substantially parallel with the surface of said form, a roller platen, a pair of interconnected toggle links connected to said carriage and platen respectively, means to reciprocate said carriage, means acting consequent upon the approach of the limit of movement of the carriage in one direction to cause the platen

to engage a work sheet superimposed on said form, and means acting consequent upon the movement of the platen in the other direction to cause the platen to be rolled across said form, means acting consequent upon the platen arriving at a variably positioned predetermined point relative to the form during its movement in the last-named direction to cause the platen to be raised clear of the form, and control means for causing the same line of the platen to coact with the same line of the printing device on successive impressions.

13. In a printing machine, the combination of means for supporting printing plates, a reciprocable carriage, a roller platen carried by the carriage adapted to coact with a printing plate in printing position or be free therefrom, means acting on one stroke of the carriage to lower the platen to active position and on another stroke to raise the platen to idle position, means for reciprocating the carriage including an operating member and an operated member, and a spring for normally holding them in operating engagement, whereby said members are normally drivingly connected by the operating member and may move independently in case of abnormal resistance to the movement of the operated member.

14. In a printing machine, the combination of a frame, two rigid arms rigidly secured to the frame and spaced apart and rising therefrom then extending substantially parallel with the top of the frame, said arms being hollow on their inner faces, a horizontal guide strip carried by each arm within the hollow space, a platen carriage having outwardly projecting studs carrying rollers which engage the upper and underfaces of said guide strips, and a magazine for address plates between the arms from which the lowermost plate in the magazine may be discharged in a direction lengthwise of the arms.

15. A printing machine having means for supporting a form and a traveling segmental platen adapted to coact with the form, an adjustable stop for the platen adapted to be set for a predetermined selected line on the form, and means for controlling the platen to cause the same line thereof to coact with the same line of the form for any given setting of the stop.

16. A printing machine having means for supporting the form, a reciprocating carriage, a platen, toggle links connecting the platen and carriage, and gearing effective to drive the platen regardless of the position of the platen or its toggle links.

17. A printing machine having means to support the form and a rigid support above the form, a rack on said rigid support, a carriage movable on the rigid support, a platen connected with the carriage by toggle links, and gearing connecting the rack with the platen.

18. A series printing machine having means to support a form and a stationary arm on which a carriage is reciprocably mounted, the carriage having connected thereto a pair of toggle links which support a roller platen and a third link interconnected between the platen axis and the carriage to guide the movement of the platen resulting from the operation of the toggle due to the reciprocation of the carriage, and wherein the stationary arm is provided with a rack which is connected to the platen by a train of gears, including a gear coaxial with the pivotal connection between the third link and the carriage and a gear coaxial with the platen.

19. The combination, with means for support-

ing a form, of a stationary platen support, a carriage shiftable on the platen support, a platen, a connection between it and the carriage, and a spring resistant member pivoted to the platen support and acting to yieldingly resist the movement of the carriage and act on the connection between the platen and carriage to cause the platen to engage a work-sheet superimposed on the form.

- 10 20. In a printing machine, the combination of a frame having means for supporting a form, a pair of arms above the frame and free therefrom; at their forward ends and having their rear ends depending and attached to the frame, said arms being spaced apart to allow forms to be fed successively between them, a platen carriage mounted on said arms for reciprocation in a plane parallel with the surface of the form, a platen carried by said carriage for movement 15 to and from said form, and means acting consequent upon the movement of the carriage in one direction to move the platen into printing coaction with the form.
- 20 21. In a printing machine, the combination of means for supporting a form, a stationary guideway spaced above said form, a carriage mounted

in said guideway, a roller platen, a pair of toggle links connected together and at their free ends connected directly to said carriage, and to the platen axes, respectively, the interconnected portions of the toggle links having abutting surfaces 5 arranged to coat with each other when the toggle is straightened to transmit the printing pressure directly from one link to the other, means to move said links to cause the platen to move into and out of contact with work superimposed on said form, and means to move the carriage in the guideway to cause the platen to roll across said form.

22. A series printing machine having means for supporting printing devices one at a time in 10 a printing position, and a stationary frame supporting a traveling roller platen for reciprocation in a plane parallel with a printing device in printing position, toggle links carrying said platen, and control means governing the rotation of 15 the platen to cause a predetermined line on the platen to come into engagement with those lines of successive printing devices which lie in the same predetermined position in the machine.
